CLAIM

The ornamental design for a hockey stick for holding pucks.

DESCRIPTION

FIG. 1 is a perspective view of a hockey stick for holding pucks showing my new design;

FIG. 2 is a side elevational view thereof, the undisclosed opposite side being a mirror image;

FIG. 3 is a front elevational view thereof;

FIG. 4 is a rear elevational view thereof;

FIG. 5 is a perspective view of a second embodiment of the hockey stick as disclosed in FIG. 1;

FIG. 6 is a reduced rear elevational view of FIG. 5; and,
FIG. 7 is a reduced front elevational view of FIG. 5.
